(57) **CLAIM**

The ornamental design for a bottle, as shown and described.

DESCRIPTION

FIG. 1 is a front elevational view of a bottle showing my new design; and,

FIG. 2 is a top, front, perspective view thereof.

The broken lines shown in the drawings are for illustrative purposes only and form no part of the claimed design.

The rear side and the bottom surface of the bottle forms no part of the claimed design invention.
